UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

MOTOR-VEHICLE.

1,177,837.

Specification of Letters Patent.

Patented Apr. 4, 1916.

Application filed April 4, 1913. Serial No. 758,845.

To all whom it may concern:

Be it known that I, SIDNEY D. WALDON, a citizen of the United States, and resident of Detroit, Wayne county, State of Michigan, have invented certain new and useful Improvements in Motor-Vehicles, of which the following is a specification.

This invention relates to motor vehicles, and particularly to the frame and the motor and to the means for supporting the motor in the frame.

One of the objects of the invention is to flexibly support the motor in the vehicle frame so that the front end of the frame may weave without disaligning the bearings of the motor, or throwing a strain upon the motor base or crank case.

Another object of the invention is to support the front end of the motor of a motor vehicle pivotally upon a cross member which extends downwardly beneath the front end of the motor, so that in the event of the failure of the pivotal connection the motor will still rest upon the cross member and will not drop out of the frame.

Another object of the invention is to so construct the front end of the motor of a motor vehicle that the front gear case cover thereof may operate to retain in position the pivot pin upon which the motor is supported.

Another object of the invention is to connect one of the cross supporting members of the motor directly with one of the bearing supporting members of the motor.

Other objects of the invention will appear from the following description, taken in connection with the drawings which form a part of this specification, and in which,

Figure 1 is a plan view of the front end of a motor vehicle embodying this invention; Fig. 2 is a side elevation of the lower part of the motor and part of the vehicle frame shown in Fig. 1; Fig. 3 is a front elevation of the vehicle shown in Figs. 1 and 2; and Fig. 4 is a vertical sectional view on an enlarged scale approximately on the line 4 of Fig. 3.

Referring to the drawings, 10 represents the forward parts of the side bars of a motor vehicle frame, and 11 is the motor base or crank case comprising the upper half 12 and the lower half or crank case cover 13. Cylinders 14 are mounted upon the base 11 and the base is formed with laterally ex-

tending integral arms 15 adjacent the rear end, which arms rest upon and are bolted to the side members 10 of the frame.

In Fig. 4 the front end of the motor crank shaft 16 is shown as mounted in the bearing 17, which bearing is secured between the enlarged portion 18 of the upper half 12 of the crank case and the bearing piece or support 19. The front end of the bottom cover or lower half of the crank case 13 makes a tight joint with the bearing piece 19, as shown at 20, in Fig. 4.

Adjacent to the front end of the motor and extending beneath it is a cross member 21 of U shape, which member rests upon the side bars 10 of the vehicle frame and is secured thereto as by the bolts 22.

The cross member 21 extends directly beneath the front end of the crank shaft 16 and beneath the bearing piece 19, which bearing piece is formed with two downwardly extending integral lugs 19' passing on either side of the cross member 21. These lugs and the cross member are drilled to receive a pivot pin 23, which thereby pivotally connects the cross member and the bearing piece 19.

The motor base or crank case 11 is formed at the front end with a gear casing 24, which extends laterally of the motor and is closed by a front cover 25. This cover is properly bolted to the casing 24, being removable therefrom, and it is provided with an integral lug 26, which extends downwardly over the head of the pivot pin 23. Thus the pivot pin 23 cannot be withdrawn until the cover 25 is removed, so that the pivot pin 23 is effectually locked in place.

A specific embodiment of the invention has been described in detail, which embodiment is deemed to be new and advantageous, and will be specifically claimed, but it should be understood that the invention is not limited to the exact details of construction shown, as it will be apparent that changes may be made without departing from the spirit or scope of the invention.

Having thus described my invention, what I claim and desire to secure by Letters Patent is:

1. In a motor vehicle, the combination with the vehicle frame comprising side bars, of a motor comprising a base having laterally extending integral arms resting upon and rigidly secured to said side bars, a cross

member at the front end of the motor also resting upon said side bars, said cross member extending beneath the front end of the motor and below the crank shaft thereof, 5 and a pivotal connection between said motor and said cross member.

2. In a motor vehicle, the combination with the motor having a front bearing for the crank shaft thereof, a bearing piece for 10 said bearing, said motor also having a front end cover, of a cross member extending beneath said bearing piece, and a pivot pin connecting said cross member and said bearing piece, said front cover having a portion 15 extending over said pivot pin for holding the latter in place.

3. In a motor vehicle, the combination with the motor, of a bearing piece for supporting the front bearing of the crank shaft, 20 means connected to said bearing piece for supporting the front end of the motor on the vehicle frame, and a bottom cover for said motor joined to said bearing piece in the rear of said connection.

25 4. In a motor vehicle, the combination with the vehicle frame comprising side bars, of a motor base having means arranged at

one end for rigidly supporting the motor on said side bars, a crank shaft and bearings therefor in the base, a bearing piece for 30 supporting one of said bearings in the base at the end of the motor opposite said rigid support, a cross member secured to said side bars and extending beneath the motor base, and a pivotal connection between said cross 35 member and said bearing piece beneath the crankshaft.

5. In a motor vehicle, the combination with the vehicle frame comprising side bars, of a motor having a crank shaft and bearing 40 therefor at one end, a bearing piece for supporting said bearing in the motor base, a cross member connected to the side bars and extending beneath said bearing piece, and a pivotal connection between said cross 45 member and said bearing piece beneath the crank shaft.

In testimony whereof I affix my signature in the presence of two witnesses.

SIDNEY D. WALDON.
